US00D954042S

(12) **United States Design Patent** (10) **Patent No.:** **US D954,042 S**
(45) **Date of Patent:** ** *Jun. 7, 2022

(54) **VIRTUALIZATION DEVICE**

- (71) Applicant: **Tangible Play, Inc.**, Palo Alto, CA (US)
(72) Inventor: **Mark Solomon**, San Jose, CA (US)
(73) Assignee: **Tangible Play, Inc.**, Palo Alto, CA (US)
(*) Notice: This patent is subject to a terminal disclaimer.
(**) Term: **15 Years**
(21) Appl. No.: **29/785,204**
(22) Filed: **May 24, 2021**

Related U.S. Application Data

- (63) Continuation of application No. 29/760,428, filed on Dec. 1, 2020, now Pat. No. Des. 920,326, which is a continuation of application No. 29/697,290, filed on Jul. 7, 2019, now Pat. No. Des. 907,032.

(57) **CLAIM**

The ornamental design for a virtualization device, as shown and described.

DESCRIPTION

FIG. 1 is a front, left perspective view of a virtualization device showing my new design;

FIG. 2 is a right, rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

Within the drawings, the broken lines show unclaimed portions of the virtualization device, and form no part of the claimed design.
